UNITED STATES PATENT OFFICE.

ARTHUR J. JOHNSON, OF ST. PAUL, MINNESOTA, ASSIGNOR TO STANDARD CONVEYOR COMPANY, A CORPORATION OF MINNESOTA.

TRANSFER GATE FOR GRAVITY CONVEYERS.

Application filed March 27, 1920. Serial No. 369,184.

To all whom it may concern:

Be it known that I, ARTHUR J. JOHNSON, a citizen of the United States, residing at St. Paul, in the county of Ramsey and 5 State of Minnesota, have invented new and useful Improvements in Transfer Gates for Gravity Conveyers, of which the following is a specification.

My invention relates to improvements in 10 transfer gates for gravity conveyers.

Its object is to provide an inexpensive and efficient device for transferring articles from a gravity conveyer to an elevator. This transfer mechanism is particularly 15 adapted to handle milk cans and similar containers which are likely to be injured or whose contents are likely to be spilled by rough handling.

A further object is to prevent congestion 20 of and injury to articles thus transferred.

The action of my device is entirely automatic. I place a gate on a gravity conveyer of common type, at a short distance 25 from the lower end of an elevator having a series of cars to which it is desired to transfer articles, and mount a lever, connected by suitable linkage to the gate, on the elevator frame. This lever is adapted 30 to be tilted by the elevator cars as they pass. Tilting the lever alternately opens and closes the gate thereby allowing articles to pass, one at a time, down the conveyer to the elevator cars.

35 In the drawings Figure 1 is a plan view of my improved transfer gate mounted on the frame of a conveyer of ordinary design and showing a horizontal section through the frame of an elevator to which milk cans are to be transferred; Fig. 2 is a plan view 40 of the gate proper with the gate arms open; Fig. 3 is a section taken on the line 3—3 of Fig. 2; and Fig. 4 is a side elevation of my improved device showing the mounting 45 on portions of a gravity conveyer and an elevator frame, together with an elevator car. The positions of milk cans being transferred are indicated in dotted lines.

50 Referring to the accompanying drawings, I have used the letter A to indicate a portion of a conveyer of common type; B a suitable vertical lift elevator; C a gate actuating lever; D gate arms and connecting linkage and E a section of rollers mounted 55 on the elevator frame.

The elevator B, shown diagrammatically in Figs. 1 and 4, is of the type having a series of car trays 1 suspended from an endless chain 2 between vertical members 3 of an elevator frame. The cars 1 have 60 wheel supports 4^a, in which two pairs of guide wheels 4 are journaled, mounted on their under side, the wheels of each pair being separated to allow vertical guides 5 (Fig. 1) to pass between them, and said cars 65 1 are formed with vertical arms 6 which are joined by pins 7 to the endless chain 2. The car trays 1 are formed in two halves with a connecting bar 8 and supporting fingers 9, the ends of the latter being separated to allow them to pass between the longitudinal roller supports 32.

The gate D is mounted on a frame 10 having transverse members 11 (Figs. 1 and 3) which are fastened in a suitable manner 75 to the under side of the gravity conveyer A. Members 12 (Fig. 4) of said frame 10 are formed with bearings 13 (Fig. 3) in which vertical shafts 14 and 15 are journaled. Gate arms 16 are keyed to the upper 80 ends of said shafts 14 and 15 and bell cranks 18 and 17 are severally keyed to the lower ends thereof. The shaft 14 has a lever 19 pivotally mounted on it above the bell crank 18 and the shaft 15 has another 85 bell crank 20 keyed to it above the bell crank 17. A link bar 21 connects the ends of bell cranks 17 and 18 and an angular link bar 22 connects the end of the bell crank 20 with the lever 19. An eye bolt 19^a is 90 mounted on the outer end of the lever 19.

The gate arms 16 are formed with in-turned ends 16^a, adapted to arrest the progress of the milk cans as they approach the elevator B when the gate is in the closed 95 position shown in Fig. 1, and their opposite ends 16^b are sharply bent inward to prevent the cans from passing the gate when it is in the open position shown in Fig. 2. The length of the arms 16 is such that when more than one milk can has arrived at the gate D, as in Fig. 1, and the gate is opened to permit the first can to pass to the elevator, the ends 16^b will be inserted between the first and second cans as shown in Fig. 2. 100

The gate actuating lever C (Figs. 1 and 4) is L shaped in cross section and has a bracket 23 (Fig. 4) bolted to it a short distance above its middle point. One end of a shaft 24 is rigidly held in the bracket 23 110

and the other end is revolute in a bearing 25, which is bolted to a horizontal member 26 of the frame of elevator B, to form a pivot for the lever C. The lever C is straight for the major part of its length and is so placed on the horizontal member 26 that when in the vertical position, (Fig. 4) one of the rollers 4 will just clear this straight surface of the lever. The upper 10 end 37 of the lever C is curved toward the elevator frame in such a manner that one of the wheels 4, on the elevator cars, as it passes this point will tilt the lever C to the position shown in dotted lines in Fig. 4. 15 The lower end 36 of the lever C is bent away from the elevator frame to present a smooth engaging surface for one of the wheels 4 when the cars pass and thus to tilt the lever C from its dotted to its full 20 line position (Fig. 4). By means of an eye bolt 27 and a rod 28 the lower end of the lever C is connected to the eye bolt 19^a on the lever 19. The rod 28 is made adjustable by a turnbuckle 29. 25 The section of rollers E is supported on a transverse member 30 (Fig. 1) of the elevator frame by means of a connecting casting 31 and a longitudinal support 32 and each roller of said section E is individually 30 supported on members 33 of the longitudinal support 32.

A stop 34 is placed at the end of the roller section E furthest from the conveyer A to prevent the milk cans from passing beyond 35 this point. The stop 34 is supported in suitable manner on a transverse member 35 of the elevator frame.

In operation, the endless chain 2, from 40 which the elevator trays 1 are suspended, being in continuous motion, said car trays pass up through the roller section E from below, the ends of the supporting fingers 9 passing on either side of the longitudinal roller support 32 and the connecting bar 8 45 passing the further end of said longitudinal support 32, and thus the fingers 9 carry the milk cans upwards as they are transferred to section E by the gate D.

As milk cans pass down the conveyer A 50 they are stopped by the ends 16^a of the gate arms 16 as shown in Fig. 1. When the arms 16 are in this position the lever C is in the position shown in full lines in Fig. 4, and the angular link bar 22, abuts against the 55 hub of the lever 19 to form a stop for the lever 19. In this position the center of the pin, which joins the link 22 and lever 19, has passed the line between centers of the shaft 14 and the pin which joins the link 22 with 60 the crank 20, so that by means of the link bar 21 and bell cranks 17 and 18 the arms 16 are effectually locked to prevent the cans from opening the gates.

Upon the arrival of an elevator car opposite the upper end 37 of the lever C, said

lever will be moved to the dotted line position, Fig. 4, and the gate arms 16 will be opened, allowing the first milk can to pass by gravity to the section E but the ends 16^b of said gate arms will restrain succeeding 70 cans from following. The first milk can, upon arriving on the section E, will come against the stop 34 and then be carried upwards by the succeeding elevator car after said car has moved the lever C to close the 75 gate arms 16. When this car comes in contact with the end 37 of the lever C the gate arms 16 will again be opened to allow another can to pass to the section E. Thus the cans will be transferred one at a time 80 to the elevator cars as they move upwards.

Having described my invention, what I claim as new and desire to protect by Letters Patent is:

1. In a device of the class described, the 85 combination with a gravity conveyer and an elevator having a series of cars, of means for allowing articles to pass singly from said conveyer to the cars of said elevator, said means comprising a gate formed with 90 an arm pivoted for horizontal movement and extending into the path of articles passing over the conveyer toward the elevator and a lever, tiltably mounted on the frame of said elevator, adapted to be moved 95 by the cars of said elevator, to actuate said gate.

2. In a device of the class described, the 100 combination with a gravity conveyer and an elevator having a series of cars, of a horizontally swinging gate arm, mounted on said conveyer, adapted to arrest the progress of packages on said conveyer and means for alternately opening and closing 105 said arm, comprising a lever tiltably mounted on the frame of said elevator and a rod joining said lever with said arm.

3. In a device of the class described, the 110 combination with a gravity conveyer and an elevator having a series of cars, of means for allowing articles to pass singly from said conveyer to the cars of said elevator, said means comprising a lever, tiltably mounted on the frame of said elevator, adapted to be tilted by the cars of said elevator, horizontally movable gate arms mounted on said conveyer, adapted to intercept packages moving toward said elevator on said conveyer, and linkage between said lever and said gate arms, whereby the tilting movement of said lever will open and close said gate arms.

4. In a device of the class described, the 115 combination with a gravity conveyer and an elevator having a series of cars, of means for allowing articles to pass singly from said conveyer to the cars of said elevator, said means comprising a frame mounted on said conveyer, gate arms journaled in 120 said frame to swing horizontally over 125

said conveyer, linkage between said gate arms to cause them to be moved in unison and a lever, tiltably mounted on the frame of said elevator, adapted to be tilted by the 5 cars of said elevator and to actuate said gate arms.

5. In a device of the class described the combination with a gravity conveyer and a vertical lift elevator having a series of cars, 10 of a frame mounted on said conveyer, vertical shafts journaled in said frame, gate arms rigidly mounted on the upper ends of said shafts and adapted to project across the path of said conveyer, a lever tiltably 15 mounted on the frame of said elevator, the ends of said lever being adapted to be engaged by elevator cars to tilt said lever, and linkage between said lever and said vertical shafts whereby the tilting movement of said 20 lever will impart an oscillating movement to said arms.

6. In a device of the class described the combination with a gravity conveyer and an elevator having a series of cars, of a frame 25 mounted on said conveyer near said elevator, vertical shafts journaled in said frame, gate arms rigidly mounted on the upper ends of said shafts and adapted to intercept packages passing down said conveyer, means mounted on the frame of said elevator to alternately open and close said gate arms and means mounted on the lower ends of said shafts to cause said gate arms to move in unison and to be locked in closed 30 position.

7. In a device of the class described the combination with a gravity conveyer and a vertical lift elevator having a series of cars, 35 of a frame mounted on said conveyer, gate arms pivotally mounted on said frame, a pair of bell cranks connected with said arms respectively, a link bar connecting said bell cranks, a lever, pivotally mounted beneath said frame, connected to one of said arms and joined by a second link bar to a second bell crank connected with the other arm, a 40 lever tiltably mounted on the frame of said elevator and adapted to be actuated by the elevator cars and an adjustable rod con-

necting said last mentioned lever with said first mentioned lever.

8. In a device of the class described the combination with a gravity conveyer and a vertical lift elevator having a series of cars, 45 of a frame mounted on said conveyer, vertical shafts journaled in said frame, gate arms rigidly mounted on the upper ends of said shafts, a bell crank keyed to the lower end of each of said shafts, a link bar connecting said bell cranks, a lever pivotally mounted near the lower end of one of said shafts and joined by a second link bar to a second bell crank on the other of said shafts, a lever tiltably mounted on the frame of 50 said elevator and adapted to be actuated by the elevator cars as they move upwards and an adjustable rod connecting said last mentioned lever with said first mentioned lever.

9. In a device of the class described the combination with a gravity conveyer and a 55 vertical lift elevator having a series of cars, of a frame mounted on said conveyer, gate arms pivotally mounted in said frame, a pair of bell cranks severally connected with said arms, a link bar connecting said pair 60 of bell cranks, a lever linked to one of said arms, a second bell crank attached to the other arm, a link connecting said second bell crank and lever, a lever tiltably mounted on the frame of said elevator and adapted 65 to be actuated by the elevator cars and an adjustable rod operatively connecting said last mentioned lever on the elevator with the lever linked to said gate arm.

10. In a device of the class described, the 70 combination with an elevator having a series of cars and a conveyer arranged to deliver packages to the cars of said elevator, a horizontally swinging gate-arm, adapted to 75 arrest the progress of packages on said conveyer and means for alternately opening and closing said gate arm, comprising a 80 lever, arranged to be actuated by said elevator, and means operatively connecting said lever with said arm.

In testimony whereof, I have hereunto signed my name to this specification.

ARTHUR J. JOHNSON.
